UNITED STATES PATENT OFFICE.

ALBERT W. WIGGLESWORTH, OF CHICAGO, ILLINOIS.

DRILLING-MACHINE.

SPECIFICATION forming part of Letters Patent No. 711,448, dated October 14, 1902.

Application filed October 14, 1901. Serial No. 78,543. (No model.)

To all whom it may concern:

Be it known that I, ALBERT W. WIGGLESWORTH, of Chicago, in the county of Cook and State of Illinois, have invented certain new and useful Improvements in Drilling-Machines; and I do hereby declare that the following is a full, clear, and exact description thereof, reference being had to the accompanying drawings, and to the letters of reference marked thereon, which form a part of this specification.

This invention relates to improvements in drilling-machines, and refers to an improved driving mechanism for the drill-spindle. Said improvements are shown as applied to that class of drilling-machines shown in the prior United States Letters Patent to Dalin, No. 462,397, granted on the 3d day of November, 1891, although the improvements may be applied to other forms of drilling-machines, as will hereinafter more fully appear.

As shown in the drawings, Figure 1 is a side elevation of a drilling-machine provided with a driving mechanism embodying my improvements. Fig. 2 is a side elevation of the speed-reducing mechanism forming part of the driving mechanism, the gears and shafts of said mechanism being shown in elevation by removal of one part of the casing or shell which normally incloses the same. Fig. 3 is a central vertical section taken through said mechanism and showing the parts thereof in a position changed from that shown in Fig. 2. Fig. 4 is an end elevation of the parts shown in Fig. 1. Fig. 5 is a sectional detail taken on line 5 5 of Fig. 2.

First referring to the improvements in the driving mechanism shown in Figs. 1 to 3, inclusive, A designates the base of the drilling-machine, and B designates a vertical tubular column rising from said base and provided at its upper end with an overhanging arm B', in the end of which is formed a vertical bearing-aperture for the drill-spindle C. D designates a work-table bracket provided at one end with a vertical opening which passes over the column B and which bracket carries at its outer end a work-table D'. E designates a drill-head which is vertically adjustable on the column and is provided on its outer end with a vertical opening, through which passes a vertically-movable spindle-bearing sleeve

C', which surrounds the drill-spindle. Said bearing-sleeve is provided with a rack C², which in the complete machine forms part of the hand-actuated feeding mechanism of the drilling-machine and also part of the counter-balance mechanism.

Now, referring to the driving mechanism and the features therein constituting my improvements, said parts are made as follows: F designates a horizontal shaft which is mounted in bearings F' F', supported on the base A, and provided on its ends with fast and loose pulleys F² F³. F⁴ designates a friction-wheel affixed to the shaft F, said friction-wheel being non-rotative on the shaft, but endwise movable thereon. G designates as a whole an oblique shaft which is revolubly mounted in its lower end in a bearing-sleeve F⁵, formed on or made integral with the bearing in which the shaft F revolves. The shaft G is a sectional shaft, or, in other words, is made of two transversely-separated upper and lower parts G' G², as shown in Fig. 3. The upper end and middle part of said shaft are mounted in bearings B² B³ on the column B and arm B', respectively. Said shaft G is provided at or near its lower end with a friction-pulley G³, having a downwardly-facing conical bearing-face which is adapted for engagement by the friction-pulley F⁴ on the shaft F. The upper end of said shaft G is provided with a beveled gear-pinion G⁴, which intermeshes with a beveled gear-wheel C³ on the spindle C. The friction-pulley F⁴ slides radially toward and from the center of the conical pulley G³ and may be actuated by any suitable mechanism—such, for instance, as shown in the prior patent to Dalin before mentioned—whereby the speed of rotation, and consequently the power of the drill-spindle, may be varied as desired, the speed of rotation of the shaft G being decreased and the power of the drill correspondingly increased as the shiftable pulley F⁴ is moved outwardly from the center of the pulley G³, and vice versa, as in the aforementioned prior patent to Dalin. The lower part G² of said shaft is provided near its upper end with an elongated gear-pinion G⁵, which is non-rotatively fixed to the shaft, as herein shown, by means of a transverse pin g, passed through the pinion and shaft in the manner shown in

- Fig. 3. The upper part G' of the shaft G is provided with a sleeve G⁶, affixed non-rotatively thereon by means of a pin g', passed transversely through the sleeve and shaft.
- 5 Said sleeve extends at its lower end beyond the part G' of the shaft, and the extended portion of said sleeve surrounds the upper end of the part G² thereof, said upper end of the part G² of the shaft rotating in said sleeve.
- 10 The lower end of said sleeve G⁶ is provided with a gear-pinion G⁷, which is made of the same diameter and has a like number of teeth as the gear-pinion G⁵. The upper end of said sleeve G⁶ is provided with a gear-wheel G⁸, which is made of somewhat greater diameter than the pinion G⁷.
- 15 H designates a short shaft which is parallel with the shaft G. Said shaft H is non-rotative and has mounted thereon a rotative sleeve H', which is provided at its lower end with a gear-wheel H², herein shown as made of the same diameter as the gear-wheel G⁸, and which gear-wheel G⁸ is adapted to mesh either with the gear-pinion G⁵ or with both
- 20 25 said gear-pinion G⁵ and the gear-pinion G⁷. Said sleeve H' is also provided at its upper end with a gear-pinion H³, shown as made of the same diameter as the gear-pinnions G⁵ G⁷, and said gear-pinion H³ is adapted to mesh 30 with the gear-wheel G⁸. The gears and shafts described constitute a speed-changing mechanism and is contained within and inclosed by a casing consisting of two separable parts I I', as shown more clearly in Fig. 4, which
- 35 are joined by bolts i, as shown in Fig. 1. On the part I of the casing is formed bearings i² i³ for the two parts G' G² of the shaft G and guides i⁴ i⁵ for the shaft H. Said casing is also provided with a babbitt bearing i⁷ for
- 40 the sleeve G⁶, which carries the gear wheel and pinion G⁸ G⁷, respectively. Said casing is provided with a lateral extension or arm I², by which it is joined to the column B, said arm being connected with the column by
- 45 screw-bolts i⁶ in the manner shown in Fig. 1. The sleeve H' revolves on the shaft H, but is held endwise immovable thereon between a collar h near the lower end of the shaft H and a pin h' near the upper end thereof
- 50 55 passed transversely through said shaft and engaging the upper gear-pinion H³. The shaft H is endwise movable in its guides i⁴ i⁵ for the purpose of shifting the gear wheel and pinion H³ H², respectively, with respect to the pinions G⁵ G⁷ and gear-wheel G⁸. Said shaft is locked in an adjusted position by means of a set-screw H⁴, which is passed through one of the lower guides i⁵ of the casing and impinges at its inner end against the
- 60 65 bottom of a groove h², formed in the lower end of said shaft, which extends outside of said casing, and the interlocking of said bolt with the groove prevents rotation of the shaft. Said set-screw is provided with a radial arm or finger-piece h³, by which it is manipulated, and the lower end of the shaft

is provided with a head or disk h⁴ for a like purpose.

When the shaft H and gear wheel and pinions H² H³, respectively, are in their uppermost positions, as shown in Fig. 2, the gear-pinion H³ is raised above and is therefore out of mesh with the gear-wheel G⁸, while the gear-pinion H² intermeshes with both of the gear-pinnions G⁵ G⁷. When the shaft G is rotated, therefore, the gear-wheel H² forms, in effect, a lock between the two parts of said shaft G, so that both parts thereof rotate at the same speed and constitute, in effect, a single shaft. When said shaft H and the parts carried thereby are in their lowermost positions, as shown in Fig. 3, the gear-wheel H² is out of mesh with the gear-pinion G⁷ and in mesh only with the gear-pinion G⁵, while the gear-pinion H³ is in mesh with the gear-wheel G⁸. The two parts of the shaft G in this instance rotate at different speeds, the upper part of the shaft being driven through the medium of the gear-wheels and pinions described from the lower part. By reason of the proportions of the gear wheels and pinions G⁵ G⁸ and H² H³ when the parts are in the positions shown in Fig. 3 the movement imparted to the upper part G' of the shaft G from the lower part G² thereof is slower than that of said lower part of the shaft, and said upper part of the shaft and connected drill-spindle will therefore be operated at a correspondingly increased power. When the parts are in the position shown in Fig. 2—that is, when both parts of the shaft G turn together—the limit of the power of the machine for this adjustment is reached when the friction-pulley F⁴ is in contact with the part of the conical pulley G³ nearest the periphery thereof, or in the position shown in Fig. 1. When doing light work, the friction-pulley F⁴ is moved close to the center of the conical friction-pulley G³, and the drill-spindle is therefore revolved at its highest or maximum speed. As the work becomes heavier the friction-pulley F⁴ is moved outwardly toward the periphery of the conical pulley, and when the extreme outer edge of said pulley is reached the limit of work of the drill is reached for the adjustment of the change-speed mechanism shown in said Fig. 2. If it be desired to operate on heavier work, the parts of the change-speed mechanism are adjusted to the positions shown in Fig. 3 and locked therein. This adjustment of the change-speed mechanism operates to decrease the speed of the drill-spindle in the manner before described, and therefore increases its power for work. The friction-pulley F⁴ may after the adjustment last mentioned be moved to its innermost position on the conical pulley G³ and exert practically the same power to drive the drill-spindle as was exerted thereby in the prior adjustment at the time said friction-pulley was engaged with the outermost part of said

conical pulley. In doing the heavier work for which the adjustment has been made the friction-pulley F^4 is then adjusted to the conical pulley to produce the required speed and power, the speed being decreased and the power correspondingly increased until the friction-pulley F^4 has again reached the outer limit of its movement. When the friction-pulley F^4 arrives at the outer limit of its movement, at a time when the adjustment of the speed-reducing mechanism is such as shown in Fig. 3, the limit of power of the drilling-machine will have been reached.

By use of the mechanism described I am enabled to greatly increase the capacity of the drilling-machine for work, and at the same time the mechanism is so constructed as to permit the machine to do the lighter classes of work with correspondingly greater speed.

It will be understood that in the drawings I have omitted for the sake of clearly illustrating the features constituting my improvements other features which may be necessary in a fully-equipped drill and that such other features may be of any type desired. It will also be obvious that many changes may be made in the structural details herein illustrated without departing from the spirit of the invention, and I do not wish to be limited to such details except as hereinafter made the subject of specific claims.

I claim as my invention—

1. In a drilling-machine, the combination with a drill-spindle, a two-part, rotative driving-shaft, said shaft being operatively connected at one end with said drill-spindle, a friction-pulley connected with the other end of said shaft, a friction driving-pulley engaging the face of said friction-pulley and movable toward and from the center thereof, and a speed-change gear connecting the parts of said driving-shaft and operable independently of the friction driving-pulley, whereby the speed of the drill-spindle may be varied by the operation of either the friction devices or the speed-change gear alone or by the combined operation thereof.

2. In a drilling-machine, the combination with a drill-spindle, of an oblique, two-part shaft rotatively mounted in bearings in the machine-frame and operatively connected with said drill-spindle, a friction-spindle on the shaft having a conical bearing-surface, a friction driving-pulley engaging said conical pulley and movable toward and away from the center thereof, and a change-speed gear connecting the two parts of said shaft and operable independently of the friction devices, whereby the speed of the drill-spindle may be varied by the independent operation of either the friction devices or speed-change gear or by the combined operation thereof.

3. In a drilling-machine, the combination with a drill-spindle, of an oblique, two-part shaft rotatively mounted in bearings in the machine-frame and operatively connected

with the drill-spindle, the two parts of said shaft abutting end to end in alinement with each other, a friction-pulley on the shaft having a conical bearing-surface, a friction driving-pulley engaging said conical pulley and movable toward and away from the center thereof, a fixed gear-pinion at the end of one part of said shaft, connected gear wheel and pinion non-rotatively mounted on the adjoining end of the other part of said shaft, the pinions on said parts of the shaft being of the same diameter, a second shaft parallel with said two-part shaft, connected gear wheel and pinion rotatively mounted on said second shaft, the gear-wheel of said second shaft being adapted to mesh with one or both pinions of said two-part shaft and the pinion of said second shaft being adapted to mesh with the gear-wheel of the two-part shaft at a time when the gear-wheel of said second shaft meshes with but one of the pinions of the two-part shaft, said gear wheel and pinion of the second shaft being endwise movable for the purpose of shifting the gear wheel and pinion thereof with respect to the gear wheel and pinions of the two-part shaft, and said gear and friction mechanisms acting independently or in combination to vary the speed of the drill-spindle.

4. In a drilling-machine, the combination with a drill-spindle, of an oblique, two-part shaft rotatively mounted in bearings in the machine-frame and operatively connected with the drill-spindle, a friction-pulley on said shaft having a conical bearing-surface, a friction driving-pulley engaging said conical pulley and movable toward and away from the center thereof, a fixed gear-pinion at the end of one of the parts of said two-part shaft, a sleeve fixed to the adjoining end of the other part of said shaft and inclosing the adjoining end of the first-mentioned part of said shaft, a gear-pinion on one end of said sleeve adjacent to and of the same diameter as the first-mentioned pinion, a gear-wheel on the opposite end of said sleeve, a second shaft parallel with said two-part shaft, connected gear wheel and pinion on said second shaft, the gear-wheel of said second shaft being adapted to mesh with one or both pinions of said two-part shaft and the pinion of said second shaft being adapted to mesh with the gear-wheel of said two-part shaft at a time when the gear-wheel of said second shaft meshes with but one of the pinions of the two-part shaft, said gear wheel and pinion of the second shaft being endwise movable for the purpose of shifting the gear wheel and pinion thereof with respect to the gear wheel and pinions of the two-part shaft, and said gear and friction mechanisms acting independently or in combination to vary the speed of the drill-spindle.

5. In a drilling-machine, the combination with a drill-spindle, of an oblique, two-part shaft rotatively mounted in bearings on the machine-frame and operatively connected with the drill-spindle, a friction-pulley on said

shaft having a conical bearing-surface, a friction driving-pulley engaging said conical pulley and movable toward and away from the center thereof, a fixed gear-pinion at one end 5 of one part of said two-part shaft, connected gear wheel and pinion on the adjoining end of the other part of said shaft, a second shaft parallel with said two-part shaft, a sleeve rotatively mounted on said second shaft provided 10 at one end with a gear-wheel adapted to mesh with one or both pinions of the two-part shaft and at its other end with a gear-pinion adapted to mesh with the gear-wheel of the two-part shaft at a time when the gear-wheel of 15 said second shaft meshes with but one of the gear-pinions of the two-part shaft, said second shaft being endwise movable in its bearings for the purpose of shifting the gear wheel and pinion thereof with respect to the gear 20 wheel and pinions of the two-part shaft, and said gear and friction mechanisms acting independently or in combination to vary the speed of the drill-spindle.

6. In a drilling-machine, the combination 25 with a drill-spindle, of an oblique, two-part shaft rotatively mounted in bearings on the machine-frame and operatively connected with the drill-spindle, a friction-pulley on said shaft having a conical bearing-surface, a friction 30 driving-pulley engaging said conical pulley and movable toward and away from the

center thereof, a fixed pinion at the end of one part of said two-part shaft, connected gear wheel and pinion on the adjoining end of the other part of said shaft, a second shaft 35 parallel with said two-part shaft, a sleeve rotatively mounted on said shaft, provided at one end with a gear-wheel adapted to mesh with one or both gear-pinions of the two-part shaft and at its other end with a gear-pinion 40 adapted to mesh with the gear-wheel of the two-part shaft at a time when the connected gear-wheel of said second shaft meshes with but one of the gear-pinions of the two-part shaft, said second shaft being endwise movable 45 in its bearings for the purpose of shifting the gear wheel and pinion thereof with respect to the gear wheel and pinions of the two-part shaft, and means for locking said second shaft in an adjusted position, comprising a set-screw passing through the bearing 50 of said shaft and engaging a longitudinal groove in the shaft.

In testimony that I claim the foregoing as my invention I affix my signature, in presence of two witnesses, this 10th day of October, A. D. 1901.

ALBERT W. WIGGLESWORTH.
